ATTORNEY

UNITED STATES PATENT OFFICE.

FRANK W. BEBERDICK, OF WEST HOBOKEN, NEW JERSEY.

DESIGN FOR A COAT-PATTERN.

SPECIFICATION forming part of Design No. 30,219, dated February 14, 1899.

Application filed November 21, 1898. Serial No. 697,105. Term of patent 14 years.

To all whom it may concern:

Be it known that I, FRANK W. BEBERDICK, a citizen of the United States, residing at West Hoboken, in the county of Hudson and State 5 of New Jersey, have invented and produced a new and original Design for a Coat-Pattern, of which the following is a specification, reference being had to the accompanying drawing, forming part thereof.

10 The drawing represents in plan view a pattern of one side and half of the back of the coat, showing my new design, and it will be understood that the other side and half of the back are the same.

15 As shown in the drawing, the leading or material feature of my design consists in the part A, forming one side and half the front and half of the back, and in the particular shape or contour given to the upper edge or 20 ends of these parts. From the point a^3 the edge of the part A extends outwardly and downwardly in a full curve to the point a' , from which point the edge of the part A extends downward in a straight line to the point 25 a .

From the point a the edge of the part A extends in a straight horizontal line, forming the bottom of the part A. From the point a^3 the edge of the part A extends downwardly in a sharply-inclined straight line to the point 30 a^8 , which deviates but slightly from the vertical, forming, with the curved line $a^2 a'$, a sharp upwardly-projecting portion. From the point a^8 the edge of the part A is curved inwardly and upwardly to the point a^5 , forming the curved line a^4 , constituting a part of 35 the neck-opening. The point a^5 is on substantially the same horizontal plane as the point a^2 . From the point a^5 the edge of the part A extends in a slight downward and then 40 upward curve to the point a^7 , forming the

compound-curved line a^6 . The point a^7 is located below the point a^5 and slightly above the point a^3 . The compound-curved line a^6 represents the shoulder line or seam. The edge of the upper portion of the part A extends downwardly and inwardly from the point a^7 in a curve deviating only slightly from a straight line to the point C^2 , from which point the said edge is curved in a small semi-circle to the point C^3 . From the point C^3 the edge of the part A extends upwardly in a curved line, deviating only slightly from a straight line to the point b . From the point b the edge of the part A extends upwardly in a straight but sharply-inclined line to the 55 point b^3 , thus giving the shape of an obtuse angle to the point b . The said point b is located opposite but slightly below the point a^7 , and is separated therefrom by the narrow space b^9 . The upper edge of the part A extends from the point b^2 in a downward curve to the point b^4 , which point is located slightly below the point b^3 , but on the same horizontal plane as the point a^5 . The outer edge of the part A extends in a straight line b^5 from the 60 extreme upper point b^4 to the extreme lower point b^6 .

Having fully described my invention, I claim as new and desire to secure by Letters Patent—

70 The design for a coat-pattern as herein shown and described.

In testimony that I claim the foregoing as my invention I have signed my name, in presence of the subscribing witnesses, this 12th day of November, 1898.

FRANK W. BEBERDICK.
